US00D773767S

(12) **United States Design Patent** (10) **Patent No.:** **US D773,767 S**
(45) **Date of Patent:** **** Dec. 6, 2016**

(54) **MOP**

(71) Applicant: **Carl Freudenberg KG**, Weinheim (DE)

(72) Inventor: **Diana Troger**, Wachenheim (DE)

(73) Assignee: **Carl Freudenberg KG**, Weinheim (DE)

(**) Term: **14 Years**

(21) Appl. No.: **29/518,731**

(22) Filed: **Feb. 26, 2015**

(30) **Foreign Application Priority Data**

Sep. 2, 2014 (EM) 002529255-0003

(51) **LOC (10) Cl.** **04-01**

(52) **U.S. Cl.**

USPC **D32/50**
